UNITED STATES PATENT OFFICE.

CURTIS W. COFFIN, OF HOLLY, COLORADO.

DRINK-MIXER.

1,298,897.

Specification of Letters Patent.

Patented Apr. 1, 1919.

Application filed February 28, 1918. Serial No. 219,677.

To all whom it may concern:

Be it known that I, CURTIS W. COFFIN, a citizen of the United States, residing at Holly, in the county of Prowers and State of Colorado, have invented certain new and useful Improvements in Drink-Mixers, of which the following is a specification.

This invention relates to agitation, and more especially it is a device for stirring the 10 contents of a glass while being drawn from a faucet, such as a fancy drink served at the soda fountain.

The object of the invention is to provide the faucet with a stirrer standing adjacent 15 and a little below the nozzle of the faucet and up over which the glass is passed in the act of bringing it in position under said nozzle, and driving the stirrer by a motor whose action is controlled by the movement 20 of the faucet handle, or driving the stirrer directly by the movement of the handle itself.

These objects are carried out in the manner described below, found in the claims, 25 and shown in the attached drawings, wherein:

Figure 1 is a side elevation illustrating one form of my invention, and

Fig. 2 is a front elevation of a faucet 30 with another form of my invention applied.

Fig. 3 is a front elevation showing diagrammatically the wiring to the motor and the switch in said wiring.

In the drawings herewith I have used the 35 letter G to indicate an ordinary glass such as is employed at soda fountains. F is the faucet, usually having a globular head H and a pendant nozzle N, and the valve within the head of this faucet is actuated by a handle which in the present case is shown as 40 composed of a yoke Y having a knob K at its top. No novelty is claimed for the parts thus far described.

The agitator forming part of this invention 45 may be said to consist of the stirrer which in the present instance is a number of blades or wings 1 mounted on an upright shaft 2 which latter is journaled in appropriate bearings 3 carried by the nozzle as best seen in Fig. 2. The stirrer stands at a point 50 near and subjacent to the nozzle, so that when the glass G is brought up under such nozzle to a point where the latter will deliver into it, it is automatically passed upward over the stirrer as shown in Figs. 1 and 55 2. Thereafter while liquid is being drawn

into the glass, means are employed to rotate the stirrer so as to agitate the contents, or in other words to mix the drink being prepared. The driving mechanism is shown in two 60 forms, respectively illustrated in Figs. 1 and 2.

In Fig. 1 the number 5 designates a small electric motor connected with the upper end of the shaft 2 and driven by a current of 65 electricity led from a suitable source along wires 6. This motor may be carried on the exterior or the interior of the head A of the faucet, but it is important that the control switch 7 shall stand in position to be actuated by the movement of the yoke Y. That is to say, as shown in Fig. 1, when the yoke Y of the handle moves forward or to the left in the act of opening the faucet, it moves in contact with the switch 7, diagrammatically 70 shown as a sliding pin in Fig. 3, and closes the circuit along the wires 6 to the motor 5, and rotation of the latter drives the agitator in a manner which will be clear; whereas on return of the handle to an upright position 75 as shown, pressure is automatically removed from the switch 7 which opens and cuts off the current and stops the rotation of the motor.

In Fig. 2 mechanical means are shown for 80 driving the upright shaft 2. Here the latter has a bevel pinion 8 on its upper end meshing with a bevel gear 9 which is fast on one arm of the yoke Y, and therefore as the handle is swung forward the comparatively 85 large gear rotates the comparatively small pinion for a number of revolutions in one direction so as to actuate the agitator, and when the handle is returned to its normal position the stirrer is actuated in the opposite 90 direction. I do not wish to be limited to any specific form of agitator or stirrer blades 95 1, nor to their exact number and disposition. The driving mechanism illustrated in Fig. 1 is set in motion by the movements of the 100 handle but actuated from its own independent source of power. The driving mechanism illustrated in Fig. 2 is both actuated and driven by the movements of the handle. But in both cases or in fact in any case the 105 driving mechanism is controlled by the movements of the handle, because such is the gist of my invention.

What is claimed as new is:

1. In a drink mixer, the combination with 110 a faucet having a handle, and a shaft carried by said faucet and having a stirrer dis-

posed near and subjacent to the faucet-nozzle; of means for controlling the action of said shaft by the movements of said handle.

2. In a drink mixer, the combination with 5 a faucet having a handle, and a rotary shaft carried by said faucet and having a stirrer disposed near and subjacent to the faucet-nozzle; of driving mechanism for said shaft controlled automatically by the opening and 10 closing movements of said handle.

3. In a drink mixer, the combination with 15 a faucet having a handle, and a rotary shaft carried by said faucet and having a stirrer disposed near and subjacent to the faucet-nozzle; of driving mechanism for said shaft, means for supplying energy to said mechanism from a remote source, and means for automatically controlling the supply of such energy by the movements of said handle.

20 4. In a drink mixer, the combination with a faucet having a handle, and a rotary shaft carried by said faucet and having a stirrer

disposed near and subjacent to the faucet-nozzle; of a motor for driving said shaft, the motor being carried by the faucet, means 25 for supplying energy to said motor, and switch mechanism for applying or cutting off said energy automatically by the movements of the faucet-handle to open position and back to closed position. 30

5. In a drink mixer, the combination with a faucet having a swinging handle, and a stirrer mounted on an upright shaft; of an electric motor mounted on said faucet and connected to said shaft, wires leading to said motor, and a circuit closer controlling said wires and disposed to be actuated by the movements of the faucet-handle. 35

In testimony whereof I affix my signature in presence of two witnesses.

CURTIS W. COFFIN.
